ELECTRIC GUITAR

Charles E. Deal, Mill Valley, Calif. 94941

Continuation-in-part of design application Ser. No. 10,554,
Feb. 13, 1968. This application June 24, 1968, Ser. No.
12,492

Term of patent 14 years

Int. Cl. D17—03

U.S. Cl. D56—1

FIG. 1 is a front elevational view of an electric guitar showing one form of my new design, wherein the upper surface is unencumbered with control knobs.

FIG. 2 is a side elevational view of the form shown in FIG. 1;

FIG. 3 is a rear elevational view of the form shown in FIG. 1;

FIG. 4 is a top plan view of the form shown in FIG. 1;

FIG. 5 is a bottom plan view of the form shown in FIG. 1;

FIG. 6 is a fragmentary front elevational view of an electric guitar showing a second form of my design wherein there are control knobs on the upper surface and modifications in the central portion beneath the strings and at the end of the strings.

The broken line showing of portions of the electric guitar to which the portions shown in solid lines is attached is for illustrative purposes only.

This application is a continuation-in-part of design

application Ser. No. 10,554 filed Feb. 13, 1968, now abandoned.

I claim:

The ornamental design for an electric guitar, substantially as shown and described.
